LIP TURNING MACHINE

John M. Whelton, Peabody, Mass., assignor to
 United Shoe Machinery Corporation, Paterson,
 N. J., a corporation of New Jersey

Application April 7, 1936, Serial No. 73,125

8 Claims. (Cl. 12—30)

This invention relates to lip turning or channel opening machines and is herein disclosed as embodied in a machine adapted to operate upon channeled outsoles of shoes from which the lasts have been removed. The invention, however, is by no means limited to use in connection with this type of work, being applicable to operations upon unattached insoles or outsoles, or upon outsoles attached to shoes from which the lasts have not yet been withdrawn. The illustrated machine is particularly useful in operations upon McKay sewed shoes and all other types of through-and-through stitched shoes, for example Littleway shoes. It enables the lip-turning operation to be delayed until immediately before the stitching and after the removal of the last, thereby avoiding any danger of closing or otherwise disturbing the turned lip when the last is removed.

It is an object of the invention to provide an improved channel opening machine. In the illustrated machine the shoe is supported internally upon a horn, while a plow operates to raise the channel lip and another tool sets the lip. In accordance with a feature of the invention means are provided for operating the plow and the lip-setting tool to feed the work.

The above and other features of the invention will become more fully evident from the description which now follows of an illustrative machine embodying the invention.

Referring to the drawings,

Fig. 1 is a perspective view of the improved machine;

Fig. 2 is a plan view of the same machine;

Fig. 3 is a view in side elevation of the upper portion of the machine;

Fig. 4 is a view in side elevation of the work-engaging instrumentalities; and

Fig. 5 is a plan view of the work-engaging instrumentalities.

The supporting structure of the machine comprises a frame 10 adapted to be secured upon a work bench. The work-engaging members comprise a plow 12 which operates to raise to upper standing position a channel lip formed on a sole, and a presser 14 which operates to complete the turning of the channel lip. The plow 12 and the presser 14 are driven in such a manner not only as to perform their respective functions, but also to cooperate in feeding the work. In order that the machine may be used to operate upon outsoles of completed shoes there is provided a support in the form of a horn 16 adapted to extend within the shoe and over which the shoe is mounted in inverted position. The horn 16 car-

ries at its upper end a small, freely rotatable button 18 which supports the sole from the interior while the operation is being performed.

The horn 16 has a depending cylindrical shank portion 20 whereby the horn is clamped for heightwise adjustment in a split lug 22 extending from a block 24. A clamping screw having a handle 26 operates to tighten or loosen the clamping pressure upon the cylindrical portion 20. The block 24 is clamped upon a vertically disposed pivot pin 28 the opposite end portions of which are mounted for free turning and sliding movement in bearings formed in upper and lower shelf-like extending portions 30 and 32, respectively, of the frame 10. The pin 28 is substantially coaxial with the button 18, which arrangement enables the horn 16 to be turned as may be necessary in manipulating the shoe without varying the position of the button 18 relatively to the tools 12 and 14. The horn 16 normally occupies a position somewhat below the operating tools to enable a shoe to be placed over the horn or to be removed therefrom. In order to raise the horn into operating position there is provided a treadle mechanism comprising a treadle bar 34 fulcrumed upon a pin 36 supported in a member 38 which is adapted to be secured to the floor. Extending upwardly from the treadle bar is a rod 40 pivotally connected at its upper end to one arm of a bell crank, 30 lever 42 which is fulcrumed upon a pin 44 secured in a lug 46 extending from the frame 10. The other arm of the bell crank 42 is pivotally connected by a pin 47 to one end of a link 48, the opposite end of which link is pivotally connected to one end of a lever 50. The lever 50 is fulcrumed upon a pin 52 secured in a lug 54 which extends from the frame 10. The opposite end of the lever 50 is bifurcated and comprises a pair of ears 56 disposed on opposite sides of the pin 28 and adapted to bear against the lower surface of the block 24. A spring 57 normally holds the treadle up. Depression of the treadle bar 34 will raise the horn 16 to its operating position. While a special stop member may be employed to limit downward movement of the treadle, it will ordinarily be satisfactory to rely upon the floor itself as a treadle stop. The horn 16 should be adjusted to the desired height in the lug 22 when the treadle is down in its stop position. The lever 42, link 48 and lever 50 are so arranged as to maintain the pin 47 always on the same side of the line joining the centers of the pins 44 and 52.

The supporting and driving mechanism of the 55

operating tools 12 and 14 will now be described. The tool 12 has formed in it a slot 58 through which extends a bolt 60 whereby the tool 12 may be clamped in any desired position of horizontal adjustment in a lever 62. The lever 62 has formed in it a horizontal guideway in which the shank portion of the tool 12 is slidably mounted for purposes of such adjustment. The opposite end of the lever 62 carries a pin 64 through which movement is communicated from an arm 66 to the lever 62. The central portion of the lever 62 has formed in it an opening 68 across which extends a trunnion pin 70 constituting a floating fulcrum for the lever 62. The opening 68 extends around a box 72 within which is formed a vertical slideway for a block 74 through which extends the trunnion pin 70. A cover plate 76 is provided for the box 72. A compression spring 78 interposed between the under surface of the plate 76 and the upper surface of the block 74 tends to hold the block and thereby the tool 12 down. The box 72 is mounted for free turning movement upon a vertical pin 80 which is secured in a bracket 82 bolted to the frame 10.

25. The arm 66 has formed in it a slot 67 in which is slidably mounted a block 69 through which extends the pin 64. The arm 66 extends from a sleeve 84 which is freely rotatable upon a pin 86 supported in suitable bearings 88 formed in the frame 10. Another arm 90 extends downwardly from the sleeve 84 and carries a cam roll 92. The roll 92 engages a slot 94 formed in a face cam 96 which is secured upon a shaft 98 journaled in bearings 100 formed in the frame 10. The shaft 98 carries a pulley 102 whereby the shaft 98 may be driven from any suitable source of power.

30. Extending rearwardly from the box 72 is an arm 104 which carries a cam roll 106 extending into a slot 108 formed in a cylindrical or barrel cam 110 which is mounted upon the shaft 98. It is evident that as the shaft 98 rotates the cam roll 106 will impart a horizontal oscillation to the lever 62 and thence to the tool 12 about the axis 45 of the pin 80 while the cam roll 92 will impart a vertical oscillation to the lever 62, the effect of which upon the tool 12 will later be described.

35. Pivotally mounted upon a pin 112 mounted in suitable bearings formed in the frame 10 is an arm 114. Fulcrumed upon a pin 116 carried in the upper end of the arm 114 is a lever 118 having a depending lug 120 through which the pin 116 extends. The tool 14 is slidably mounted for horizontal adjustment in a guideway formed in the end of the lever 118. A clamping bolt 122 extending through a horizontal slot 124 in the tool 14 secures the tool to the lever in a desired position of horizontal adjustment. The rear end of the lever 118 is pivotally connected by means 40 of a pin 126 to a rod 128, the lower end of which rod is freely slidable through a diametrical opening in a pin 130. A compression spring 132 surrounding the rod 128 is interposed between a shoulder 133 on the upper portion of the rod 128 and the pin 130. A nut 134 threaded upon the rod 128 and secured thereupon by a lock nut 136 adjustably limits the expansion of the spring 132 and prevents the end of the rod 128 from sliding through the opening in the pin 130. The pin 130 is carried in the end of an arm 138 which extends from a sleeve 140 freely rotatable upon the pin 86. An extension 142 from the arm 138 carries a cam roll 144 which engages a cam slot 146 formed in a face cam 148 mounted upon the shaft 98.

5. Integral with the bar 114 is an extension 150 which carries a cam roll 152 engaging a slot 154 formed in a face cam 156 mounted upon the shaft 98. It will be observed that as the shaft 98 rotates the cam roll 152 will oscillate the bar 114 about the axis of the pin 112 which will cause an oscillation in an in-and-out direction of the tool 14 while at the same time the cam roll 144 will oscillate the lever 118 about the pin 116 and thereby impart to the tool 14 vertical oscillation. 10. In operating the machine a shoe having an outsole O and an upper U is mounted upon the button 18 with the horn 16 extending within the upper of the shoe. The outsole O has formed upon it a lip L which is to be raised by the machine. The lip L is first engaged by the plow 12 which raises the lip to upstanding position, whereupon the lip is turned over away from the margin of the sole and is pressed downwardly by the tool 14 as the work advances. The oscillatory movements of the lever 62 are such as to cause the plow 12 to bear downwardly in gripping engagement with the base of the channel formed on the outsole O and to feed the sole while so gripping it. The base of the channel is that portion of the sole which, before the lip L is raised, lies directly under the lip L. At the termination of the feeding movement the gripping pressure is released, and the plow is retracted while the sole is held stationary by the presser 14. It is in the course of its retraction or back-feed movement that the plow operates to raise the lip L. The gripping pressure of the plow is obtained by upward movement of the pin 64 derived from the cam 96, which upward movement compresses the spring 78 as the lever 62 fulcrums about the locality of engagement of the plow 12 with the work. The release, or substantial release, of this pressure is obtained by downward movement of the pin 64. The vertical movement of the plow 12 20 is equivalent to the extent to which the material is compressed. The plow 12, during its back-feed movement, drags along the surface of the work piece. The yielding of the spring 78 not only accommodates local variations of thickness in the same work pieces but also renders unnecessary a change in the heightwise adjustment of the horn 16 for work pieces which differ somewhat in thickness. 30. 40. 45. 50. 55. 60. 65. 70. 75. As the plow 12 approaches the end of its feeding movement, the presser 14 moves outwardly with respect to the machine or inwardly and transversely with respect to the sole, at the same time moving downwardly to clamp the sole against the button 18. The plow 12 pauses at the end of its feed stroke, maintaining its pressure against the work until the presser 14 has arrived at clamping position. The presser 14 operates to hold the sole clamped during the retraction or back-feed movement of the plow 12. At the end of its back-feed movement the plow 12 again comes to rest, maintaining its pressure against the work until the pressure 14 releases its clamping pressure and begins its movement of retraction. The presser 14 completes its retraction and begins its advance while the plow 12 is feeding the work. The presser 14 is provided with an overhanging extension 158 the under surface of which bears upon the upturned lip L and exerts a wiping or ironing action upon the lip to press the lip flat, as shown in Fig. 4. The vertical movement of the presser 14 is greater than the vertical movement of the plow 12. The spring 132 accommodates variations in thickness of the 75.

workpiece. Those portions of the surfaces of the plow 12 and the presser 14 which engage the margin of the outsole are preferably roughened to increase their gripping characteristics.

- 5 It will be observed that the plow 12 operates as a feed foot in its advancing movement and as a plow to raise the channel lip in its back-feed movement while the presser 158 operates both as a pressure foot to hold the work during 10 the back-feed of the plow 12 and also as a pressing or ironing member to set the lip L. Figures 4 and 5 show the plow 12 at the end of its feeding stroke and just about to release the work from its gripping pressure while the presser 14 is at the end 15 of its outward and downward stroke and is just clamping the work stationary.

Having thus described my invention, what I claim as new and desire to secure by Letters Patent of the United States is:

- 20 1. A channel opening machine comprising a horn adapted to support internally the sole of a shoe, a plow for raising a channel lip formed on the sole, a tool for setting the lip, and means for operating said plow and said lip-setting tool to 25 feed the work.
2. In a channel opening machine, a plow for raising a channel lip formed on a sole, said plow being constructed and arranged for heightwise movement relatively to the sole and also for 30 movement along the line of feed, means for oscillating said plow along the line of feed, and means for pressing said plow against the base of the channel during each advance of the plow to feed the work and for relieving the pressure of the 35 plow during each retraction of the plow.
3. In a channel opening machine, a pair of tools constructed and arranged respectively to raise a channel lip formed on a sole of a shoe and to set the lip in open position, a horn adapted 40 to extend within the shoe for supporting the sole, means for imparting an oscillatory feeding movement to said lip-raising member to cause said lip-raising member in its advance movements to feed the sole, and means for operating said lip-setting 45 tool to set the lip in open position and during the back-feed movements of said lip-raising member to hold the sole clamped against said horn.
4. In a channel opening machine, a feed member engageable with the base of a channel formed 50 on a sole, said feed member being mounted for heightwise movement relatively to the sole, means for oscillating said feed member along the line of feed, and means operable without substantial heightwise movement of said feed member at the 55 locality of engagement between the feed member and the sole, to press said feed member against the sole during each feeding movement and to relieve the pressure of said feed member during each retraction.
5. In a channel opening machine, a feed mem- 60
- ber engageable with the base of a channel formed on a sole, a support for said feed member constructed and arranged for oscillatory movement of said feed member along the line of feed, a floating fulcrum for said support, means acting upon 5 said support to swing said support about said fulcrum in a direction to cause said feed member to press against the base of the channel during the advance movements of the feed member, and resilient means for yieldably supporting said 10 floating fulcrum and for maintaining said feed member against the base of the channel upon release of feeding pressure.
6. In a channel opening machine, a feed foot engageable with the base of a channel formed on 15 a sole, a lever upon which said feed foot is carried, a spring-yieldable fulcrum for said lever, means for relatively swinging said lever about said fulcrum to cause said feed foot, as said fulcrum yields, to press against the channel base, a 20 support for said fulcrum pivotally mounted to enable said feed foot to move in the line of feed, and means operating upon said fulcrum support to cause oscillation of said feed foot along the line of feed, said swinging means being 25 oscillatory and operating to press the feed foot against the channel base during the advance of the feed foot and to release the pressure of the feed foot during retraction.
7. In a channel opening machine, a lip-raising 30 tool, a lip-setting tool, means for oscillating said lip-raising tool in the line of feed of the work, a cam mechanism to which said lip-raising tool is connected, said cam mechanism being constructed and arranged to cause the lip-raising tool to press 35 against the work during its advancing movements to feed the work and to release its pressure against the work during its back-feed movements, and means for operating said lip-setting tool to set the lip and to hold the work stationary 40 during the back-feed of the lip-raising tool.
8. In a channel opening machine, a lip-raising tool, a lip-setting tool, four driven cams, mechanism operated by one of said cams for oscillating said lip-raising tool in the line of feed of the 45 work, mechanism operated by another of said cams for causing said lip-raising tool to press against the work during its advancing movements to feed the work and to release its pressure against the work during its back feed movements, mecha- 50 nism operated by another of said cams for oscillating said lip-setting tool transversely of the line of feed to wipe the upturned lip inwardly from the margin of the sole, and mechanism operated by the remaining cam for oscillating said 55 lip-setting tool in a heightwise direction relatively to the work to set the lip and to hold the sole stationary by clamping pressure during the back-feed movement of said lip-raising tool.

JOHN M. WHELTON. 60

CERTIFICATE OF CORRECTION.

Patent No. 2,099,042.

November 16, 1937.

JOHN M. WHELTON.

It is hereby certified that error appears in the printed specification of the above numbered patent requiring correction as follows: Page 2, second column, line 64, and page 3, first column, line 9, for the word "pressure" read presser; and that the said Letters Patent should be read with these corrections therein that the same may conform to the record of the case in the Patent Office.

Signed and sealed this 22nd day of February, A. D. 1938.

Henry Van Arsdale,
Acting Commissioner of Patents.
